DESIGN FOR A TYPEWRITER ERASER

Benjamin W. Hanle, Elizabeth, N. J., assignor to Eagle Pencil Company, New York, N. Y., a corporation of Delaware

Application April 18, 1941, Serial No. 100,487

Term of patent 14 years

To all whom it may concern:

Be it known that I, Benjamin W. Hanle, a citizen of the United States and residing at Elizabeth, in the county of Union and State of New Jersey, have invented a new, original, and ornamental Design for Typewriter Eraser, of which the following is a specification, reference being had to the accompanying drawing, forming part thereof and in which

Fig. 1 is a plan view of one side of a typewriter eraser embodying my new design,

Fig. 2 is a plan view of the opposite side thereof, and

Fig. 3 is an edge view thereof.

The dominant feature of my design resides in a typewriter eraser having an imperforate concave hub protruding at its beveled rim from the plane of the eraser disk, as shown.

I claim:

The ornamental design for a typewriter eraser, substantially as shown and described.
